UNITED STATES PATENT OFFICE.

FRANK M. HILL, JR., OF SALEM, NEW JERSEY.

GLASS-BLOWING MACHINE.

No. 829,210.

Specification of Letters Patent.

Patented Aug. 21, 1906.

Application filed April 5, 1906. Serial No. 310,092.

To all whom it may concern:

Be it known that I, FRANK M. HILL, Jr., a citizen of the United States, residing at Salem, in the county of Salem, State of New Jersey, have invented a new and useful Glass-Blowing Machine, of which the following is a specification.

My present invention relates to glass-blowing machines; and it consists of a novel construction of lifting mechanism by means of which the pressed blank is automatically removed from the press-mold.

It further consists of a novel construction coacting with the movement of the plunger to raise or lower the blow-head.

It further consists of a novel construction of lifting-rod and its adjuncts.

It further consists of other novel features of construction, all of which will be herein-after fully set forth.

Figure 1 represents a front elevation of a glass-blowing machine embodying my invention. Fig. 2 represents a sectional plan view on line *x* *x*, Fig. 1. Fig. 3 represents a front elevation of a portion of Fig. 1 in detached position. Fig. 4 represents a sectional plan view on line *y* *y*, Fig. 3. Fig. 5 represents, on an enlarged scale, a front elevation of a portion of Fig. 1 partly in section. Fig. 6 represents a plan view of Fig. 5. Fig. 7 represents, on an enlarged scale, a sectional view of a portion of Fig. 1. Fig. 8 represents a side elevation of another embodiment of lifting mechanism which may be employed. Fig. 9 represents a sectional plan view of the lifting mechanism shown in Fig. 8, showing the same in operative position with respect to a neck-mold.

Similar numerals of reference indicate corresponding parts in the figures.

Referring to the drawings, 1 designates the base of the machine, supported on suitable rollers or wheels 2 and provided with a conductor 3, by means of which the machine may be readily moved to a desired position.

4 designates a standard rising from the base 1, having at its upper end a support 5, between which and the table 6 is interposed a ball-bearing 7. The table 6 has mounted thereon in any suitable manner blow-molds 8 and press-molds 9, said blow-molds and press-molds being of the usual or conventional type, provided at their upper end with a substantially plane surface 10, upon which

the neck-mold or ring 11 is adapted to be seated. The neck-mold 11 comprises two members 12 and 13, hinged together at 14, there being handles 15 and 16 extending from the members 12 and 13.

17 designates a cylindrical support or standard extending above the table 6 and having supported at a suitable point thereon the cylinder 18, in which is mounted a plunger 19, having an operative end 20.

21 designates a bar or plate fixed on the plunger-rod 19 and having extending therefrom the rods 22, the outer ends of which are threaded and provided with suitable nuts 23.

24 designates a bar or plate loosely mounted on the rods 22 and between which and the plate 21 are interposed the cushioning-springs 25, so that the bar or plate 24 is normally maintained in its uppermost position.

26 designates a lifter-rod which passes through the plates 21 and 24, said rod having a slot or recess 27 therein with which a plate or pawl 28 engages, said plate or pawl 28 being secured to the plate 24 by a pin, screw, or equivalent device 29.

30 designates a washer or collar mounted on the rod 26 above the plate 24, the upward movement of said washer being prevented by means of a pin or equivalent device 31.

32 designates a set-collar mounted on the rod 26 intermediate the bars or plates 21 and 24, there being a spring 33 interposed between the set-collar 32 and the plate 21, whereby said lifter-rod is normally maintained in raised position. The lower end of the rod 26 is enlarged, as at 67, it being most clearly seen in Fig. 3 that this enlargement 67 extends angularly from the lower end of the rod 26.

68 designates a fork pivoted at 69 to the enlargement or plate 67, said fork having the two members 70 and 71, the downward movement of said members being prevented by their engagement with the plate 67, as indicated in Fig. 1.

72 designates lugs extending from the members 12 and 13 near the front end thereof and between the handles 15 and 16, the arm 71 engaging with said lug during the lifting operation.

82 designates a block or bracket fixed on the plunger-rod 19, said block being guided by a rod 34, extending therethrough and engaging the plates 21 and 24. 35 designates a

- cam or lever arm having an inclined face carried by said block 82 and coacting with one end of a lever 36, pivoted at 37 to a bracket 38, carried by the standard or upright 17. 5 73 designates a slot in the other end of said lever 36, with which a pin 39 engages, said pin being secured to one end of a lever 40, fulcrumed at 41 to the bracket 38, the other end of said lever engaging a collar or washer 42, carried by the valve rod or stem 43, which is guided in arms 44, extending from the bracket 38, the upper end of said valve-rod 43 extending into a stuffing-box 74, which is connected with a pipe 45 in communication with the main inlet-pipe 46, said pipe 46 having leading therefrom a pipe 47, which communicates with the valve mechanism 48, which is controlled by a suitable lever 49. 10 20 Loosely mounted on the valve-rod 43 is a blow-head 50, the lower end 51 thereof being adapted to closely engage the neck-mold, there being an aperture 52 extending through the bottom 51 and communicating with an internal chamber 53 of the blow-head. 25 54 designates a hollow disk or valve head located at the lower end of the tube 43, said disk having thereon a washer 55, which engages the annular seat 56 of the blow-head 50. 30 57 designates openings extending through the valve-head 54 and communicating with the chamber 58. 59 designates a standard suitably recessed, as at 60, said standard having mounted 35 therein a rod 61, the upper end of which engages a socket 62 in the table 6, there being a shoulder 63 near the upper end of said rod. 64 designates a handle adjustably mounted on the rod 61. 40 65 designates a spring interposed between the handle 64 and the bottom of the recess 60, it being seen in Fig. 1 that this rod extends through the bottom support 1. 66 designates a pressed-glass blank. 45 75 and 76 designate lugs which prevent improper movement of the neck-mold. In the embodiment shown in Figs. 8 and 9, instead of employing a single lifter-rod, as 26, having a fork pivoted at its lower end, I employ a plurality of such rods, each of said rods having an arm pivoted thereto, which engage, respectively, the hinge of the neck-mold and the lugs 72 on the opposite side thereof. In this embodiment 77 designates 50 a plurality of lifting-rods having at their lower ends a plate or stop 78 extending angularly therefrom. 79 designates a fork pivoted at 80 to the rods 77, said fork having extending therefrom the arms 81. One of 55 the arms 81 engages the hinge 14, and the other of said arms engages the lugs 72, which are located on the opposite side of the neck-mold. 60 I have deemed it unnecessary to show the manner in which the rods 77 are carried by 65 the spring-plates 21 and 24, since they would be mounted in a similar manner to the rod 26, the only difference being that I employ a plurality of lifter-rods and instead of employing a fork pivoted at the lower end thereof I employ a single arm, as indicated in Fig. 9, and the operation of this embodiment will be similar to that already described with respect to the lifter-rod 26 and its adjuncts. 70 The operation of the device is as follows: 75 Having the parts in the position seen in Fig. 1, the operator places a ball of glass of a desired size in the press-mold, which is at this time in operative position under the presser-head 20, or which is moved into such a position, it being understood that the table 6 is provided with a desired number of sockets 62, with which the end of the rod 61 engages, so that when the rod is seated in one of the sockets of the table 6 a press-mold and 80 a blow-mold will be in operative position under the blow-head and the presser-head. The operator now admits motive fluid to the pressing mechanism 18 by actuating the handle 49, which causes the plunger 19 and the 85 mechanism carried thereby to move downwardly, it being understood that at this time a ball of glass is in the press-mold and that the neck-mold is in operative position on the press-mold. As the plunger and its adjuncts move downwardly the arms 70 and 71 of the 90 fork 68 contact with the handles 15 and 16 and the hinge of the neck-mold, and, since this fork is pivoted at 69 to the rod 26, as the rod 26 moves downwardly the fork will turn 95 upwardly, as seen in Fig. 3, and will pass below the arms 15 and 16 and the hinge 14, it being noted that, owing to the provision of the recess 27 in the rod 26 and the pawl 28, carried by the plate 24, the rotation of said 100 fork 68 will be positively prevented. The 105 presser-head 20 engages the glass blank and forms the same in the usual manner. As the plunger-rod 19 moves downwardly the arm 35, carried by the block 82, will 110 move downwardly therewith, thus permitting the lever 36 to turn on its fulcrum, said lever 36 coacting with the lever 40 by means of the pin thereon and the recess or slot in the lever 36, thus permitting the valve-pipe 115 43 to move downwardly, so that as the presser-head 20 moves into operative position with respect to the glass blank the bottom 51 of the head 50 will engage a blow-mold and close the top of the same. As the 120 rod 43 moves downwardly the washer 55 will be removed from its seat 56 in the valve-head and the motive fluid in the chamber 58 will be permitted to pass therefrom into the chamber 53, thence through the aperture 52 125 into the blow-mold, in which a pressed-glass blank has heretofore been placed, and this blank is now formed into the shape or con-

tour of the blow-mold in the usual manner. When the pressing and blowing operations are completed, the lever 49 is actuated in a reverse direction, thus admitting motive fluid 5 to the presser-head 18, and thereby raising the plunger 19 and its adjuncts. As the plunger is moved upwardly the arms 70 and 71 of the lifter-fork 68 engage, respectively, the lugs 72 and the hinge of the neck-mold, and 10 said neck-mold, together with the pressed-glass blank adhering thereto, is raised from the press-mold, it being seen that the lifter-rod 26 is yieldingly supported owing to the interposition of the spring 33 between the 15 set-collar 32, carried by said rod, and the plate 21, through which said rod passes. As the arm 35 of the block 82 is carried upwardly by the movement of the plunger it engages the lever 36, thus causing said lever 20 to turn on its fulcrum 27, and owing to the slot 73 therein and the pin 39 coacting therewith the lever 40 will be turned on its fulcrum and the end of said lever coacting with the collar on the valve-stem will cause said 25 valve-stem to be raised. As the valve is raised the washer 55 is seated in a positive manner against the seat 56 of the blow-head 50, thereby closing the admission of motive fluid to the chamber 53 and raising the blow-head 50 above the blow-mold, as will be apparent from Figs. 1 and 7.

It is to be noted that the lifting mechanism is yieldingly supported, so that there is no shock or jar as the lifter-fork engages the 35 handles and hinge of the neck-mold on its downward movement. It will be further apparent that with the pressing and blowing mechanisms are simultaneously actuated and are controlled by a single lever, so that 40 when the operations of pressing and blowing have been completed and the parts raised, as seen in Fig. 1, a pressed-glass blank will be raised above the press-mold in a position convenient to the operator for removing said blank therefrom and placing it in a blow-mold, it being seen that the blow-head at this 45 time is raised above the blow-mold in such a position that the blown glass therein may be readily and quickly removed and a pressed-glass blank placed therein for the next blowing operation.

From the above description it will be apparent that I have produced a novel and useful construction of lifting mechanism carried 55 by the reciprocating plunger and a novel construction in which the blowing mechanism is controlled by the movement of said pressing-plunger, and while I have shown in the present instance the preferred embodiment 60 thereof it is to be understood that it is susceptible of modification in various particulars without departing from the spirit or scope of my invention or sacrificing any of its advantages. It will be further apparent

that while in the present instance I have 65 shown as the preferred embodiment of my invention a single lifter-rod having a pivoted member adapted to engage with the neck-mold a plurality of such lifter-rods having a pivoted member at the lower end thereof 70 may be employed and still be within the scope of my invention. It will also be apparent that owing to the lifter-rod 26 passing freely through the plates 21 and 24 if the lifter-rod descends to such a position 75 that the lower end thereof engages the table 6 or any obstruction thereon, the lifter-rod 26 being loosely mounted between the plates 21 and 24, the downward movement of said 80 plates with respect to the lugs 26 will be permitted, as is clearly indicated in Fig. 1, and the pivoted member will be suitably cushioned on its upward movement owing to the provision of the spring 33, interposed between the set-collar 32 and the plate 21, as 85 will be evident to those skilled in this art. It will be further apparent that while I have referred to the members 67 and 78 as being "plates" it is to be understood that these are simply stops carried by the lifter-rods in 90 order that the pivoted fork or arms on their upward movement will be maintained in a suitable horizontal position.

Having thus described my invention, what I claim as new, and desire to secure by Letters Patent, is—

1. In a glass-blowing machine, pressing and blowing mechanism, press-molds and blow-molds, a lifter member yieldingly carried by said pressing mechanism, a fork 100 hinged to said lifter member, a stop for said fork, a neck-mold with which said fork is adapted to engage, and means intermediate said pressing and blowing mechanism for actuating the latter.

2. In a glass-blowing machine, a support, pressing mechanism carried thereby, a rotatable table, press-molds and blow-molds carried thereby, a neck-mold adapted to be seated on said molds, a lifter member carried by 110 said pressing mechanism, means pivoted thereon adapted to engage said neck-mold on its upward movement, a stop for limiting the downward movement of said means, means for preventing the rotation of said lifter 115 member, blowing mechanism controlled by said pressing mechanism, and means for controlling said pressing mechanism.

3. In a glass-blowing machine, press-molds and blow-molds, a neck-mold adapted 120 to be seated on said molds, a pressing plunger, means for actuating said plunger, a plate carried thereby, rods extending from said plate, a second plate engaging said rods, nuts at the ends of said rods, springs interposed between said plates, a lifter member 125 engaging said plates, means for preventing the rotation of said member, and means piv-

oted at the lower end of said member adapted to engage said neck-mold and raise the same on its upward movement together with the pressed-glass blank.

5 4. In a glass-blowing machine, a pressing-plunger, means for actuating said plunger, a block carried by said plunger, a lever adapted to coact with said block, a second lever coacting with said first lever, a valve-stem 65 70 coacting with said second lever, a blow-head through which said valve-stem passes, and having valve-seats therein, and a valve-head carried by said stem adapted to engage said seats.

15 5. In a glass-blowing machine, a base, a table rotatably supported thereon, press-molds and blow-molds carried thereby, means for locking said table in a desired position, a neck-mold adapted to be seated on 20 said molds, said mold comprising two hinged members, handles extending from each member, lugs carried by said members, pressing mechanism, blowing mechanism controlled thereby, a lifting device yieldingly carried by said pressing mechanism, said lifting device having a fork pivoted at its lower end adapted to engage said lugs and said hinge on its upward movement to raise the neck-mold and blank adhering thereto above a press-mold.

25 6. In a glass-blowing machine, a reciprocating plunger, means for actuating said plunger, a block carried thereby having a cam-face at one end thereof, a lever one end of which coacts with said cam-face, the other end of said lever having a slot therein, a second lever, a pin at one end thereof engaging said slot, a movable valve-stem adapted to be actuated by said second lever, a blow-head 30 35 on said valve-stem and a valve-head carried by said stem adapted to coact with said blow-head to control the passage of motive fluid therethrough.

40 7. In a glass-blowing machine, a rotatable table, press-molds and blow-molds carried thereby, neck-molds adapted to be seated on said molds, said neck-mold comprising two hinged members, handles extending from said members, lugs carried by said members, a reciprocating plunger, means for actuating the same, a lifting member yieldingly carried by said plunger and having a plate at its lower end, a fork pivoted at the lower end of said member with which said plate engages 45 50 55 to prevent its downward movement, and blowing mechanism actuated by said plunger.

8. In a glass-blowing machine, a rotatable table, a support above said table, a bracket carried by said support having arms extending therefrom, a reciprocating plunger, means for actuating said plunger, a block carried by said plunger, a lever pivoted to said bracket and coacting with said block, said lever hav-

ing a slot in one end thereof, a second lever pivoted to said bracket, a pin at one end thereof engaging said slot, a movable valve-stem passing through the arms of said bracket, a collar on said stem with which the end of said second lever coacts, a spring interposed between one of said arms and said collar, a blow-head mounted on said stem having a valve-seat therein, said blow-head having an aperture through the bottom thereof, and a valve-head carried by said stem engaging said seat to control the passage of motive fluid through said blow-head.

9. In a glass-blowing machine, a base, rollers on which said base is mounted, a conductor secured to said base, a support rising from said base, a table rotatably mounted on said support, means carried by said base for locking said table in a desired position, press-molds and blow-molds mounted on said table, neck-molds adapted to be seated on said molds, said neck-mold comprising two members hinged together, handles carried by each member, lugs extending from said members, a support above said table, pressing mechanism carried thereby having a reciprocating plunger, a plate fixed to said plunger, rods extending from said plate, a second plate mounted on said rods, springs interposed between said plates, nuts at the ends of said rods, a lifting-rod passing through said plates, means for preventing the rotation of said lifting-rod, a washer at the top of said rod, a set-collar on said rod intermediate said plates, a spring interposed between said set-collar and the lower end of said plates, a fork pivoted at the lower end of said lifter-rod, and means for limiting the downward movement of said fork, said lifter-rod engaging with said lugs and said hinge to raise the neck-mold on its upward movement, and blowing mechanism controlled by said pressing mechanism.

10. In a glass-blowing machine pressing and blowing mechanism, press-molds and blow-molds, a lifter member yieldingly carried by said pressing mechanism, a fork hinged to said lifter member, a neck-mold with which said fork is adapted to engage, and means for actuating said pressing and blowing mechanisms.

11. In a glass-blowing machine, a base, a table rotatably supported thereon, press-molds and blow-molds carried thereby, means for locking said table in a desired position, a neck-mold adapted to be seated on said molds, said mold comprising two hinged members, handles extending from each member, lugs carried by said members, pressing mechanism, blowing mechanism, means for actuating said blowing mechanism, and a lifting device yieldingly carried by said pressing mechanism, said lifting device having a fork pivoted at its lower end adapted to en-

gage said lugs and said hinge on its upward movement to raise the neck-mold and blank adhering thereto above a press-mold.

12. In a glass-machine, a press-mold, a pressing mechanism, a lifter member yieldingly carried thereby, a member pivoted to said lifter member, a neck-mold with which said pivoted member is adapted to engage, a

stop for limiting the downward movement of said pivoted member, and means for actuating said pressing mechanism.
